Houdaille-Hershey Corporation, Detroit, Mich.,
a corporation of Michigan

Application September 8, 1944, Serial No. 553,194

5 Claims. (Cl. 62—126)

1

This invention relates to heat exchangers having header chambers and spent fluid conveying ducts extending above the header chambers to insure complete usage of heat exchange fluid before it leaves the heat exchanger.

Specifically the invention deals with a stamped sheet metal evaporator unit having a bottom and side walls containing refrigerant-distributing ducts together with header chambers in the side walls and spent refrigerant ducts extending above the header chambers in the side walls. The invention utilizes portions of evaporator side walls to not only suspend the evaporator unit from the top wall of a refrigerator cabinet for spacing a refrigerated shelf of the unit beneath the liner of the cabinet to prevent frosting of the liner, but to also provide refrigerant ducts capable of extracting the last traces of heat-absorbing capacity from the refrigerant.

The sheet metal U-shaped evaporator units as commonly used in domestic mechanical refrigerators are usually suspended from the top wall of the refrigerator cabinet. In some cases, it is undesirable to have heat-absorbing evaporator surfaces closely adjacent the walls of the cabinet, because the cooling effect of these surfaces tends to induce frost formation on the cabinet walls. In installations where the top wall of the evaporator unit, or where the top shelf of a refrigerator unit, is refrigerated and positioned closely adjacent the top liner wall of the refrigerator cabinet, excessive frosting of this liner wall occurs and, upon defrosting the unit, it is very difficult to remove the water between the unit and the top wall of the refrigerator.

According to the present invention, portions of the side walls of a U-shaped sheet metal evaporator unit are utilized to space the top shelf of the unit sufficiently beneath the top liner of the refrigerator cabinet from which the unit depends to prevent frosting of the liner, and these same side wall portions are also utilized to provide spent refrigerant ducts extending upwardly from the header chambers in the side walls. Thus the side wall portions above the top shelf and above the header chambers of the unit serve a dual function; of spacing the heat-absorbing surfaces of the unit sufficiently from the liner of the refrigerator cabinet to prevent frosting of the liner, and simultaneously providing ducts which convey spent refrigerant out of the unit while absorbing the last traces of refrigerating capacity from the refrigerant.

It is, then, an object of the present invention to provide heat exchanger units with discharge

ducts in portions of the unit serving to mount the unit in desired relationship to a support.

Another object of the invention is to provide suspension walls of heat exchangers with embossments forming ducts for heat exchange fluid beyond the normal duct passage arrangement of the units.

A specific object of the invention is to provide a sheet metal evaporator unit with side wall mounting portions that space heat-absorbing surfaces of the unit from a support, and also contain spent refrigerant ducts.

Another specific object of the invention is to utilize the metal in a sheet metal evaporator unit for the dual function of suspending the unit in spaced relation from the top wall of a refrigerator cabinet, while providing passages for refrigerant to absorb the last traces of refrigerating capacity from the refrigerant.

20 A still further object of the invention is to provide a U-shaped sheet metal evaporator unit having a refrigerated top wall or shelf, and side wall portions extending above said top wall or shelf carrying mounting flanges on their upper ends and being embossed to define spent refrigerant passages.

25 A still further object of the invention is to provide a sheet metal U-shaped evaporator unit having side walls with header chambers therein, a refrigerated shelf bridging the side walls above the header chambers, and side wall portions extending from the header chambers above the refrigerated shelf having horizontal flanges at their upper ends for receiving mounting members, together with embossed ducts therein sloping back toward the header chambers to convey spent refrigerant from the header chambers while allowing drainage of entrained unspent refrigerant back to the header chambers.

30 35 40 Other and further important objects of this invention will be apparent from the disclosures in the specification and the accompanying drawing.

On the drawing:

Figure 1 is a fragmentary front end elevational view of an evaporator unit according to this invention mounted in a refrigerator cabinet.

Figure 2 is a top plan view of the evaporator unit of Figure 1.

Figure 3 is a side elevational view of the evaporator unit of Figure 1.

As shown on the drawing:

In Figure 1, the reference numeral 10 designates generally a refrigerator cabinet having a top liner wall 11, and side liner walls 12 cooperating to define a chamber C. A heat exchange

unit 13 of this invention is mounted in the chamber C in spaced relation from the liner walls 11 and 12 by means of suspension bolts 14 secured in the top wall of the cabinet 10.

The unit 13 is composed of embossed brazed or welded-together metal sheets or plates, including an inner sheet 15 and an outer sheet 16. The sheets 15 and 16, after being secured together, are bent so as to provide a bottom 13a, spaced opposed vertical side wall portions 13b, 13b, and inturned top flanges 13c, 13c at the upper ends of the side wall portions 13b, 13b. These flanges 13c, 13c receive the mounting bolts 14 therethrough, and rubber blocks 17 are interposed between the flanges and the liner 11 to insulate the flanges from contact with the liner.

A shelf 18 bridges the side walls 13b, 13b in spaced relation beneath the flanges 13c, 13c and has downturned sides 18a, 18a secured by means of rivets 19 or the like fastening means to the side walls. The shelf 18 is composed of a pair of embossed brazed or welded-together metal sheets or plates, including a top sheet 20 and a bottom sheet 21.

A back wall 22 is provided for the unit. This back wall 22 has peripheral flanges 22a around the edges thereof respectively riveted to the rear end of the shelf 18, the side walls 13b, 13b, and the bottom wall 13a by means of rivets 23. The back wall 22 is also preferably embossed as at 22b to stiffen the same, so that very light gauge metal can be used.

The outer sheet 16 of the unit 10 has an embossment 24 extending from the front to the rear of the bottom 13a of the unit midway between the side walls 13b, 13b. This embossment 24 cooperates with the inner sheet 15 to provide an inlet manifold duct for the unit.

The outer sheet 16 has a plurality of spaced parallel embossments 25 extending from the embossment 24 along the bottom 13a and side walls 13b, 13b of the unit to merge into enlarged embossments 26, 26 extending in a front-to-rear direction along the side walls 13b, 13b at levels beneath the shelf 18. The inner sheet 15 has similar embossments 26 aligned with the embossments 26 on the outer sheet, and the aligned embossments cooperate to define header chambers in the side walls of the unit for receiving refrigerant from the upper end of the refrigerant distributing ducts provided by the embossments 25.

The top sheet 20 of the shelf 18 has an embossment 27 extending along its rear edge and equipped with a nipple portion 27a at one end thereof receiving a tube 28 which extends in back of the unit 10 to an embossed nipple portion 24a of the embossment 24 for connecting the ducts provided by the embossments 27 and 24.

The bottom sheet 21 of the shelf 18 has a serpentine embossment 29 defining a duct communicating with the end of the duct provided by the embossment 27 and extending to the front end of the shelf as shown in dotted lines in Figure 2, and thence rearwardly to a nipple 30 provided on the top sheet 20. This nipple 30 receives a tube 31.

Refrigerant is fed to the unit 13 through the tube 31 and flows through the duct provided by the embossment 29 and through the duct provided by the embossment 27 of the shelf to refrigerate the shelf. Refrigerant from the shelf flows from the tube 28 to the manifold duct provided by the embossment 24. This manifold duct distributes the refrigerant to the distributing

ducts provided by the embossments 25. The refrigerant boils out of the tops of the distributing ducts into the header chambers provided by the embossments 26.

Serpentine embossments 32 are provided in the outer sheet 16 of the unit 13 to form spent refrigerant ducts in the portions of the side walls 13b which lie above the header chambers. The embossments 32 are arranged so that the spent refrigerant ducts communicate with the front ends of the respective header chambers and thence wind upwardly along a constantly inclined path to levels just beneath the flanges 13c, 13c. The inner sheet 15 of the unit 13 has nipples 33 embossed thereon in communication with the discharge ends of the ducts provided by the embossments 32. These nipples receive discharge tubes 34.

Spent refrigerant vapor from the header chambers rises upwardly through the ducts provided by the embossments 32 to the discharge tubes 34. Any unspent refrigerant entrained in the spent refrigerant ducts will absorb heat since the spent refrigerant ducts have heat-absorbing areas and are integral with the side wall portions of the unit above the shelf 18. The spent refrigerant ducts, in addition, slope constantly backward toward the header chambers so that liquid refrigerant entrained in the spent refrigerant vapor, if present in quantities which are not completely vaporized, will flow back to the header chambers. The spent refrigerant ducts are substantially horizontally disposed, but continually slope back to provide for a counter-current flow of spent and unspent refrigerant therein.

The shelf 18 is refrigerated, since it receives refrigerant from the inlet tube 31 and conveys this refrigerant through the transfer tube 28 to the evaporator unit proper. The inlet manifold of the evaporator unit then distributes the refrigerant through the refrigerated ducts in the header chambers and spent refrigerant from the header chambers is conveyed in the outlet tubes 34 through the spent refrigerant ducts lying above the header chambers and above the shelf 18. The spent refrigerant ducts are provided in portions of the side walls of the unit which are utilized to space the refrigerated shelf 18 from the top liner 11 so that the liner 11 will not be frosted.

From the above descriptions it will be understood that the heat exchangers of this invention utilize wall areas to space heat-absorbing surfaces thereof from surrounding surfaces, while providing ducts for spent heat exchange fluid.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A heat exchanger comprising a U-shaped member having headers in the side legs thereof in spaced relation beneath the upper ends of the side legs, ducts extending around the side legs and bottom of the U-shaped member communicating with the headers, inturned flanges on the tops of the legs above the headers, serpentine ducts having superimposed elongated runs in the portions of the legs between the headers and the flanges communicating with the tops of the headers to convey spent heat exchange fluid from the headers, and spent refrigerant outlets at the upper rear ends of the serpentine ducts.

2. A heat exchanger comprising a pair of secured-together contiguous metal sheets bent into the shape of a U and having a horizontal bottom and vertical sides, said sheets being embossed to define a header chamber in each vertical side in spaced relation from the top thereof, a second pair of secured-together contiguous metal sheets secured to said vertical sides above said headers and below the tops of said sides, and additional embossments in the portions of said sides between said headers and the tops of the sides providing ducts for spent heat exchange fluid from said headers.

3. An evaporator unit comprising a pair of contiguous bonded-together metal sheets bent to form the bottom and side walls of a sharp freezing chamber, said sheets being embossed to define refrigerant-distributing ducts along the bottom and side walls and header chambers in the side walls intermediate the tops and bottoms thereof communicating with said ducts, a second pair of contiguous secured-together metal sheets providing a shelf with an embossed refrigerant-circulating duct, means securing said shelf to said side walls at a level adjacent the tops of the header chambers in the side walls, said side walls having mounting flanges at the upper ends thereof spaced materially above said shelf, and the portion of said side walls between said header chambers and said flanges being embossed to provide serpentine refrigerant-conveying ducts com-

municating with the tops of the header chambers and having superimposed oppositely inclined portions extending from the front to the rear of the unit and arranged to drain refrigerant back into the header chambers, a refrigerant supply tube communicating with one end of the duct in the shelf, a connecting tube joining the other end of said duct in the shelf with said refrigerant-distributing ducts, and spent refrigerant-receiving tubes communicating with the upper ends of the ducts above the header chambers.

4. In an evaporator unit having header chambers in the side walls thereof the improvement of side wall portions extending vertically above said header chambers and containing refrigerant-conveying ducts communicating with the tops of the header chambers, said ducts having superimposed inclined runs along the length of said wall portions and sloping toward the header chambers.

5. In a U-shaped sheet metal evaporator unit having header chambers in the sides of the U, the improvement of vertical side walls above said header chambers embossed to define serpentine spent refrigerant-conveying ducts extending to the tops of the legs and sloping back toward the header chambers to permit countercurrent flow of spent refrigerant gases from the header chambers and unspent liquid refrigerant back to the header chambers.

BERNARD C. JOHNSON.
